CLAIM

The ornamental design for an exercise device, as shown and described.

DESCRIPTION

FIG. 1 is a front view of an exercise device.

FIG. 2 is a rear view of the exercise device of FIG. 1.

FIG. 3 is a left side view of the exercise device of FIG. 1.

FIG. 4 is a right side view of the exercise device of FIG. 1.

FIG. 5 is a top view of the exercise device of FIG. 1.

FIG. 6 is a bottom view of the exercise device of FIG. 1.

FIG. 7 is an isometric view of the exercise device of FIG. 1.

FIG. 8 is a front view of another exercise device.

FIG. 9 is a rear view of the exercise device of FIG. 8.

FIG. 10 is a left side view of the exercise device of FIG. 8.

FIG. 11 is a right side view of the exercise device of FIG. 8.

FIG. 12 is a top view of the exercise device of FIG. 8.

FIG. 13 is a bottom view of the exercise device of FIG. 8; and,

FIG. 14 is an isometric view of the exercise device of FIG. 8.

In the illustrated design of FIGS. 1 through 7, the dash-dot-dot-dash lines represent a boundary between a first appearance and a contrasting appearance.
